UNITED STATES PATENT OFFICE

ORVILLE O. SMITH, OF PRESCOTT, ARIZONA, ASSIGNOR OF ONE-HALF TO LOUIS E. HESLA
AND WALTER H. DUNCAN, BOTH OF PRESCOTT, ARIZONA

PUMP

Application filed March 25, 1930. Serial No. 438,805.

My invention relates to an improvement in horizontally disposed rotary pumps of the eccentric type. This application is substituted for my former application Serial No. 5 748,354, filed November 7, 1924.

This present pump is of the rotary eccentric type, having pump vanes which are reciprocated and rotated by the eccentric mechanism, and the object of the invention is to 10 improve the construction and operation of pumps of this character.

In the accompanying drawings:

Fig. 1 is a side elevation of the complete pump;

15 Fig. 2 is a transverse sectional view through the housing;

Fig. 3 is a top view of the housing;

Fig. 4 is an outside view of the eccentric housing cover removed;

20 Fig. 5 is a top plan view of the same;

Fig. 6 is an inside elevation thereof;

Fig. 7 is a face view of the pump vane 25 guide-ring;

Fig. 8 is a plan view of the same;

Fig. 9 is a plan view of one of the vanes;

Fig. 10 is an end view thereof; and

Fig. 11 is an edge view of the same.

A, represents the base of the eccentric pump; and 1 is a housing secured thereto by 30 screws or bolts 2; and 3 is a line of shafting extending through the housing and through a bearing 4 supported by the base A and on which shaft 3 are mounted pulleys 6.

An eccentric housing cover 7 is adapted 35 to be bolted onto the open (or left-hand end as shown in the drawings) of the housing 1, and this cover 7 carries a stub-shaft 8 which extends into the housing and has a bore 9 eccentrically disposed therein, as shown in 40 Figs. 2, 5 and 6. The shaft 3 extends through and is journaled in the bore 9.

Keyed on the shaft 3 at a point between the end of the stub-shaft and the inner vertical wall of the housing is a pump vane 45 guide-ring 10 shown in Figs. 2, 7 and 8. This

ring is fitted to turn in the recess 14 formed in the housing 1, which recess is concentric of the shaft 3 and eccentric of the inner cylindrical wall 15 of the housing. The cylindrical portion of the guide-ring 10 fits and 50 turns in the recess 14 of the housing, and is provided with four equidistant transverse slots 11 as shown in Figs. 7 and 8; and the two pump vane cores 12a shown in Figs. 9, 10 and 11 are assembled with their slots 13 55 at right-angles to each other and receiving and in contact with the stationary stub-shaft 8, as shown in Fig. 2. Vanes 12 extend transversely from opposite sides of the vane cores 12a, as shown in Fig. 2.

60 The water enters the pump through the port 16 and is discharged through the port 17.

65 Thus it will be seen that the pump vane guide-ring 10 turns with the shaft 3 in the circular recess 14 in the inner wall of the housing, which it fits, while the pump vanes having sliding connection therewith are turned around the stationary stub-shaft 8 as a center with their outer edges following the 70 wall 15 of the housing, the centers of the rotary and stationary shafts being eccentric to each other. In this way the water is drawn or sucked in through the inlet port 16 and discharged through port 17 with each cycle 75 of the pump vane ring-guide.

Thus in a very simple manner, a strong, durable and effective type of eccentric pump is provided which carries on with precision, 80 and pumps the water in a continuous stream under pressure while in operation.

I claim:

85 A pump of the character described comprising a housing having a chamber therein, a stationary shaft disposed in said chamber, a rotary shaft journaled eccentrically of the stationary shaft, a cylindrical guide member having a flange at an end thereof fixed to the rotary shaft at one side of the chamber, said guide member having radially extending slots 90

in the outer wall thereof, a single pair of vane cores disposed in the chamber and having openings therein receiving the stationary shaft, the cores being arranged side by side within the cylindrical guide member, vanes extending radially in different directions from each of the vane cores and movable through the slots in the guide member, the vanes carried by each core being extended laterally on one side only thereof and overlapping the other core of the pair.

In testimony whereof I affix my signature.

ORVILLE O. SMITH.
